UNITED STATES PATENT OFFICE.

WILHELM B. BRONANDER, OF MONTCLAIR, NEW JERSEY, ASSIGNOR TO AMERICAN MACHINE & FOUNDRY COMPANY, A CORPORATION OF NEW JERSEY.

PACKAGE WRAPPING.

Application filed November 13, 1925. Serial No. 68,863.

This invention relates to an improvement in package wrapping, particularly to package wrapping with cellulose hydrate and the like.

5 In wrapping packages or boxes of candy, fruit, cigarettes, and numerous other commodities, the transparent materials known as cellulose hydrate and glassine paper are frequently used, to enhance the appearance of 10 the package or box, and to hermetically seal its contents. Materials of this kind have the undesirable inherent property of shrinking with age and atmospheric changes, and as 15 ordinarily used on packages or boxes, surrounding the same, they shrink and internal stresses are set up therein which result in tearing the material and thus defeating its purpose when packages wrapped with it are stored for a considerable time, or exposed to 20 cold air for a short time. The shrinkage is slow when the material is aging in an even temperature, but very rapid in a sudden drop of temperature. It has been found to be practically impossible to allow for this 25 shrinkage in wrapping packages, for to wrap them loosely detracts from the smooth appearance that is regarded as essential.

It has been discovered that this difficulty can be overcome by using cellulose hydrate 30 or similar material to cover the major part only of the surface or surfaces of the package or box to be wrapped, and by using either transparent glassine or common opaque paper, to cover the remainder of the 35 surface or surfaces of said package or box, the edges of the two materials being overlapped and sealed by wax the elasticity of 40 which permits the shrinking cellulose hydrate to creep or slip on the paper, without tearing either and without breaking the seal. The production of such a wrapper is the 45 main object of the present invention. Another object is its production by a method which is employed during the application of the wrapping materials to the package or box. With these and other objects not specifically mentioned in view, the invention 50 consists in certain constructions of wrapper, and in certain methods of making the same, which will be hereinafter fully described and 55 then specifically set forth in the claims hereunto appended.

In the accompanying drawings, which 55 form a part of this specification and in which like characters of reference indicate the

same or like parts, Fig. 1 is an inverted perspective view of a candy box having a wrapper constructed in accordance with the invention; Fig. 2 is a side elevation of the same, shown partly in section; and Fig. 3 60 is an inverted plan view of the same, showing parts of the bottom cover torn away.

In carrying the invention into effect, there is provided a sheet of wrapping material which shrinks with age and atmospheric 65 changes, and which is large enough to cover the major part only of a package or box to be wrapped. There is further provided a smaller sheet, of wrapping paper, which is large enough to cover the remainder of the 70 package or box, and which has edges overlapping the edges of the shrinkable material. And there is further provided a seal of wax, between the overlapping edges of the two 75 sheets of wrapping material, the elasticity 80 of which permits the shrinking material to creep or slip on the paper as it becomes smaller, whether slowly as it ages in an even temperature, or rapidly as when it is exposed to cold air. In the best methods of 85 carrying the invention into effect, and where a box is to be wrapped, the cellulose hydrate, or other shrinkable material, is folded over the top, the sides, and the ends of the box, and under its bottom, but adjacent the edges 90 only of the latter; and the bottom cover is of waxed paper slightly smaller than the bottom of the box, but large enough to overlap the bottom folds of the cellulose hydrate, far enough to provide an efficient seal when its 95 wax is softened by heat to join the two sheets of wrapping material, yet not far enough to develop a holding force in excess of the tensile strength of the cellulose hydrate and paper.

Referring to the drawings, 4 indicates a candy box having an overhanging top and bottom, and 5 is a cellulose hydrate wrapper so folded as to cover the top, the sides, and the ends of the box 4, and having edges, as 100 at 6, underlying the bottom of the box, adjacent the edges of the latter. A bottom cover 7, of transparent waxed paper, which is slightly smaller than the bottom of the box, has edges overlapping the edges of the 105 cellulose hydrate on the box bottom. When the two wrapping materials are thus placed in position on the box, with their edges overlapping, heat is applied to the waxed edges 110 of the bottom cover 7; and this results in

hermetically sealing and holding the cellulose hydrate part of the wrapper and the paper part of the same together. The wax is on one side only of the paper.

5 As the cellulose hydrate, stretched snugly over the top, sides and ends of the box, shrinks, the internal stresses set up therein by the resistance of the box cause it to pull its edges, underlying the bottom of the box, 10 out from under the paper bottom cover 7 to some extent. The elasticity of the wax seal which holds the overlapped edges of the two parts of the wrapper together, permits this creeping or slipping of the cellulose hydrate 15 on the paper, without breaking the seal. And since the holding force of the wax is less than the tensile strength of the cellulose hydrate and paper, the wax yields and neither the cellulose hydrate nor the paper is 20 torn during the creeping movement. The shrinkage of the cellulose hydrate around the edges of the bottom of the box is indicated in the lower right corner of Figs. 2 and 3, the original position of its edge being indicated by the dotted lines at 8, and its position after shrinkage being indicated by 25 the full lines at 9 (Fig. 3).

Although the cellulose hydrate shrinks as before, the package or box thus wrapped 30 presents the desired smooth and pleasing appearance, not only when freshly wrapped, but at all stages of cellulose hydrate shrinkage.

What is claimed is:

35 1. A package wrapper having a part made of material which shrinks with age and atmospheric changes, and a part made of paper, the edges of said parts being overlapped and sealed by wax which permits the shrinking material to slip on the paper without tearing either and without breaking the seal.

40 2. A package wrapper having a part made of cellulose hydrate, and a part made of 45 waxed paper, the edges of said cellulose hydrate and said paper being overlapped and sealed by the wax of said paper which permits the shrinking cellulose hydrate to slip on said paper without tearing either and without breaking the seal.

45 3. A package wrapper having a part made of a sheet of material which shrinks with age and atmospheric changes and covering the major part of the package, and a part 50 made of a smaller sheet of paper covering the remainder of said package, the edges of said parts being overlapped and sealed by wax which permits the shrinking mate-

rial to slip on the paper without tearing either and without breaking the seal.

55 4. A box wrapper having a part made of a sheet of cellulose hydrate and covering the tops, the sides, and the ends of the box, and underlying the bottom of the box adjacent its edges only, and a part made of a sheet of waxed paper slightly smaller than the bottom of the box and overlapping the edges of the sheet of cellulose hydrate, the overlapping edges of the cellulose hydrate and paper being sealed by the wax of the 60 paper which permits the sheet of cellulose hydrate to slip on the paper without tearing either and without breaking the seal.

65 5. The method of wrapping a package, which consists in folding a sheet of wrapping material which shrinks with age and atmospheric changes over a part only of the 70 surface of the package, then placing a sheet of paper over the remainder of said surface with its edges overlapping the edges of the shrinking material, then sealing the overlapping edges by wax the elasticity of which permits the shrinking material to slip on the 75 paper without tearing either and without breaking the seal.

80 6. The method of wrapping a package, which consists in folding a sheet of cellulose hydrate over the major part only of the 85 surface of the package, then placing a sheet of waxed paper over the remainder of said 90 surface with its edges overlapping the edges of the cellulose hydrate, then heating the 95 waxed paper where its edges overlap the edges of the cellulose hydrate to seal the overlapping edges together, the elasticity of the wax permitting the cellulose hydrate to slip on the paper as it shrinks, without tearing either and without breaking the seal.

100 7. The method of wrapping a box, which consists in folding a sheet of cellulose hydrate over the top, the sides, and the ends of the box, with its edges underlying the bottom of the box adjacent its edges only, then placing a sheet of waxed paper over substantially the whole of the bottom of the box 105 with its edges overlapping the edges of the cellulose hydrate, then heating the waxed paper where its edges overlap the edges of the cellulose hydrate to seal the overlapping edges together, the elasticity of the wax permitting the cellulose hydrate to slip on the 110 paper as it shrinks, without tearing either and without breaking the seal.

In testimony whereof, I have signed my name to this specification.

WILHELM B. BRONANDER.
